US00D939696S

(12) **United States Design Patent** (10) **Patent No.:** **US D939,696 S**
Uridil et al. (45) **Date of Patent:** **** Dec. 28, 2021**

(54) **APPLICATOR**(71) Applicant: **Medline Industries, LP**, Northfield, IL (US)(72) Inventors: **Morgan Uridil**, Evanston, IL (US); **Amanda Roszkowiak**, Schaumburg, IL (US)(73) Assignee: **Medline Industries, LP**, Northfield, IL (US)(**) Term: **15 Years**(21) Appl. No.: **29/691,096**(22) Filed: **May 14, 2019**(51) LOC (13) Cl. **24-02**

(52) U.S. Cl.

FOREIGN PATENT DOCUMENTS

JP 2001000536 1/2001
WO 2008048856 4/2008

Primary Examiner — T Chase Nelson

Assistant Examiner — Kelly L Gross

(74) Attorney, Agent, or Firm — Fitch, Even, Tabin & Flannery LLP

(57) **CLAIM**

The ornamental design for an applicator, as shown and described.

DESCRIPTION

FIG. 1 is a top perspective view in accordance with an embodiment of our new design;
FIG. 2 is a bottom perspective view thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a right side elevational view thereof; and,
FIG. 8 is a left side elevational view thereof.
